16 Claims. (Cl. 103—2)

1

This invention relates to apparatus for delivering liquids and viscous materials (hereinafter referred to as liquids) and applies in all cases wherein liquid is to be fed under pressure from a container to a plurality of individual points.

For instance the invention has particular reference to lubricating systems in which a pump or propelling device is employed for feeding lubricant to a number of separate positions as in the case of chassis lubrication for road vehicles, or in stationary machinery.

Our invention applies to that kind of apparatus which includes liquid propelling means, such as a pump supplying liquid to a rotary distributor and means for driving the rotary distributor so that it delivers the liquid to each of a number of delivery conduits in succession. Such apparatus is disclosed in our prior U. S. Patent No. 2,157,970.

One of the objects of the present invention is to provide improved apparatus for delivering liquids and viscous materials under high pressure by means of a rotary distributor co-operating with a stationary ring having a number of conduits wherein a delivery arm on the rotary distributor is maintained in pressure contact with the ring during delivery and wherein this pressure is relieved so that the rotary distributor can turn from one position to another under light load supplied by a spring between the delivery periods.

A further object of the present invention is to deliver at any desired pressure a given quantity of liquid without loss due to leakage between the contacting faces of the rotary distributor and the member having the conduits to which the liquid is fed.

According to the present invention some or all of the pressure applied to operate the pump plunger is transmitted during pump delivery, and while the rotary distributor is stationary, to the contacting faces of the rotary distributor and the member having the conduits in a direction to prevent their separation, and the relation between the cross sectional area of the pump plunger, the area of contact between the contacting faces of the delivery arm of the rotary distributor and the member having conduits, and the cross sectional area of the passage through which the liquid is forced, is such that the load on the pump plunger or this load plus the pressure of a spring acting on the distributor produces a pressure at the contacting faces of the delivery arm of the rotary distributor and the member having the conduits equal to or in excess of that required to ensure a seal between these contacting surfaces.

The pressure between the contacting surfaces due to load on the pump plunger is preferably removed after each delivery stroke of the

2

pump and when the rotary distributor is moving around its axis but light pressure is maintained between the contacting surfaces by a spring acting on the distributor.

5 Movement of the pump plunger on the delivery stroke is preferably produced by a mechanically driven rotary member which is provided with means for producing mechanically the rotary movement of the distributor during the return movement of the pump plunger.

For instance the endwise movement of the pump plunger on the delivery stroke may be produced by a face cam mounted on an axis which is parallel to the axis of the rotary distributor and the face cam may have an eccentric pin engaging an oscillating member mounted on the rotary distributor, the oscillating member carrying a pawl engaging a ratchet wheel fixed to the rotary distributor.

15 The rotary distributor may have a pump portion of cylindrical form mounted for rotation in a circular opening in the ring having the conduits, the face of the ring being engaged by a delivery arm on the distributor, a body formed as a hollow casing being secured to this ring, this body containing the cam for producing the delivery stroke of the pump plunger and the endwise pressure on the pump plunger being transmitted to the rotary distributor and to its delivery arm.

25 Further the rotary distributor may be provided with one or more balancing arms engaging the face of the ring and angularly spaced away from the delivery arm so that when pressure is applied to the rotary distributor parallel to the axis of the pump and at right angles to the engaging faces of the ring and the delivery arm, there will be no tendency to tilt the distributor.

30 Pivoted to the casing we may provide an idler arm carrying a roller engaging the operative surface of the cam, the idler arm acting upon a member which engages the pump plunger. By this means the side thrust produced by the rotation of the cam is absorbed and not transmitted to the pump plunger.

35 The body of the appliance may serve to enclose worm or other reduction gear by which the cam operating the pump plunger is driven.

40 The appliance is preferably driven from a rotating part of the vehicle or machine, such, for instance, as the speedometer drive, so that the number of pump deliveries is proportional to the mileage of the vehicle, or, in the case of stationary machinery to the length of time the mechanism is run.

45 Referring to the drawings:

50 Figure 1 is a plan view partly in section showing one construction in accordance with the invention.

Figure 2 is a section on line 2-2 of Figure 1. Figure 3 is a section on line 3-3 of Figure 2. Figure 4 is an end view of the cam. Figure 5 is a section on line 5-5 of Figure 2. Figure 6 is a section on line 6-6 of Figure 2. Figure 7 is a sectional view of a part of the apparatus illustrating a modification.

In the construction illustrated the body of the appliance comprises a casing 10 which is open at one end 11 and contains a ring 12 having a circular row of conduits 13, extending parallel to its axis, for receiving the deliveries of liquid. This ring 12 is detachably secured by screws 14 to the flange 15 of a cap 16 closing the end of the casing 10 and secured thereto by bolts 17. The flange 15 is provided with an equivalent number of conduits 18 to which delivery pipes 19 are attached, leading away to the positions where the lubricant is required. Each of the conduits 18 contains a non-return valve 20. This part of the arrangement may be similar in principle to that disclosed in our prior British specification No. 459,946.

An opening is provided through the ring 12 in which is fixed a bearing 21 and mounted in this bearing is the rotary distributor 22. The rotary distributor 22 projects through the bearing 21 in the ring and the end of the distributor which projects through the bearing is enclosed by the cap 16.

The rotary distributor comprises a cylindrical body part 23 having an inlet port 24 and a discharge port 25 for the lubricant and having an axial cylindrical passage 26 in which the endwise moving pump plunger operates. This pump plunger is in two parts 27, 28, one of which 27 is positively operated in one direction by a cam 29 and returned by a spring 30 acting on a washer 31 engaging a collar 32 on the part 27, while the other part 28 is spaced away from the end of the part 27 and is acted upon by a spring 33 tending to move it towards the plunger part 27.

In the cylinder 26 in which these parts work, there is a gap 34 between the two parts 27, 28 of the pump plunger and this gap becomes filled with liquid through the inlet port 24 in the cylindrical body 23 of the rotary distributor.

The two parts 27, 28 of the pump plunger move together with liquid imprisoned between their adjacent ends until the gap 34 containing the liquid registers with the discharge port 25. This port is provided with a non-return valve 35.

The two parts of the pump plunger move in an endwise direction with the liquid to be pumped imprisoned between their adjacent ends until this liquid is moved to a position opposite the delivery port 25, and a shoulder 36 near the end of the part 28 of the plunger comes into contact with a cap 37 secured to the end of the rotary distributor body. Delivery then takes place and during delivery the cam pressure acting upon the pump plunger is transmitted by the shoulder 36 to the rotary distributor body and keeps a delivery arm 38 on the said body in pressure contact with the ring 12 having the conduits through which delivery takes place.

The delivery arm 38 and the body 23 of the distributor are provided with a delivery passage 39 leading to a passage 40 in a plug 41 mounted in the end of the delivery arm and engaging the face of the ring 12.

The spring 30 operating to keep the face of the plug 41 in contact with the face of the ring 12 at all times to allow pressure to be generated as the pump plunger is operated.

The delivery arm 38 is also preferably provided

with a branch passage 42 communicating with the passage 39, the passage 42 being normally closed by a spring loaded safety valve 43 which can be set to open at any predetermined pressure. 5 This permits of the escape of the liquid back into the casing should the pressure in the pipe exceed the said predetermined pressure.

In order to balance the rotary distributor against the offset pressure between the end of the 10 delivery arm 38 and the ring 12, the rotary distributor is provided with two further arms 44, 45 extending in a direction opposite to that of the delivery arm and having facings 46 engaging the ring 12. Instead of engaging the ring 12 the balancing arms may engage any other suitable structure such for instance as the flange 15.

These two further arms are spaced apart by a relatively small angle and fixed to the rotary distributor between these arms is a registering 20 device incorporating a pawl 47 pivoted at 48 to the arm 44 and acted upon by a spring 49 mounted on a pin 50 on the arm 45, this pawl engaging in succession the teeth of a ratchet wheel 51 fixed on the bearing 21 so as to ensure 25 the correct positioning of the delivery end of the passage through the delivery arm in line with one of the receiving conduits in the ring, and preventing return movement of the distributor after it has been moved by the means now to 30 be described.

The rotary distributor is given a step by step rotation so that delivery is made at successive operations of the pump to separate conduits in the ring 12.

35 For this purpose the rotary distributor has attached to it a ratchet wheel 52 which is acted upon by a pawl 53 pivoted at 54 upon an oscillating ring 55, which ring is mounted upon a projecting cylindrical part 56 of the rotary distributor. The arrangement is such that the ring is oscillated by means of an eccentric pin 57 on the rotary cam 29 provided within the casing of the appliance, which cam is used for producing the endwise movement of the pump plunger.

40 The oscillating ring 55 is provided with an arm 58 having a pin 59 on which is mounted a spring 60 acting on the pawl 53. Further the oscillating ring 55 is provided with a radial slot 61 in which slides a square block 62 mounted on the eccentric pin 57.

45 Rotation of the cam 29 causes the pin 57 to move in a circular orbit and the movement is translated by the block 62 moving in the radial slot 61 into an oscillating movement of the ring 55 causing the pawl 53 to advance the ratchet wheel 52 and the rotary distributor by one step. Backward movement of the rotary distributor on the return stroke of the ring 55 is prevented by the pawl 47 which engages with the stationary 50 ratchet wheel 51.

55 The pump plunger has one end enclosed in a cap 63 which is engaged by the end of the plunger 27. The spring 30 produces the return movement of the pump plunger.

60 The screwed cap 37 receives the endwise pressure from the pump plunger 28 during the delivery stroke and this cap is provided with a pair of jaws 64 engaging flats upon a sleeve 68 screwed to the projecting end of the pump plunger 28.

65 Means are provided for adjusting the gap between the adjacent ends of the two parts 27, 28 of the pump plunger so that the volume of liquid delivered at each delivery stroke can be adjusted, and such means may take the form of a transverse pin 65 extending through the cap 16, this

pin having an eccentric portion 66 operating on a flange 67 at the end of the sleeve 68.

This pin can be turned on its axis and secured by the nut 69 to effect adjustment in the volume of the delivery.

Movement of the pin 65 through an angle of 180° effects an adjustment of the distance between adjacent ends of the parts 27, 28 from maximum to minimum and the end 86 of the pin 63 is of non-circular form so that it can readily be turned and is provided with a flange 87 having a portion which moves between two stops formed on the exterior of the cap 16 so that rotary motion of the pin 65 is limited to 180° and the position of the flange 87 in relation to the stops will give an indication of the position of the eccentric part 66 of the pin in various adjusted positions.

For driving the pump plunger on the delivery stroke the cam 29 is provided and this is mounted to rotate about an axis parallel with that of the rotary distributor and is driven by worm gear 70, 71 situated within the appliance. The casing of the appliance is provided with bearings 72 for the worm shaft 73 on which is the worm 70 engaging the worm wheel 71 fixed upon the cylindrical boss 74 of the cam 29.

The worm is preferably fixed or formed intermediate the ends of the worm shaft 73 and both ends of the worm shaft are mounted in bearings 72 in the casing and both ends may be formed or provided with means whereby they may be placed in driving engagement with a driving shaft, in which case the arrangement would be such that the worm shaft can be driven from either end and in either direction. Instead of making both ends of the worm shaft 73 with means so that they may be engaged by a driving shaft, the construction illustrated in Figure 1 may be employed and if it is desired to drive from the opposite side of the casing, the bearings 72 are taken out and placed in the opposite sides of the casing from the position shown in Figure 1, the shaft 73 being placed in the opposite way round. The cam 29 is symmetrical on either side of its highest point and for either direction of rotation it produces the necessary reciprocating movement of the pump plunger and the eccentric pin produces the step by step rotation of the rotary distributor.

The cam is mounted upon a sleeve-like hub 75 formed on a plate secured to the casing and the cam has a flange 76 which is secured to the side of the worm wheel which rotates with its opposite side in contact with the aforesaid plate. The cam is a face cam, the face 77 being formed at the edge of the flange 76 on the cam which is secured to the side of the worm wheel.

An idler arm 78 is pivoted at 79 within the casing containing the cam and at right angles to the axis of the cam. At its free end the idler arm is provided with a roller 80 bearing on the operative face of the cam and adjacent the roller, the idler arm is provided with a facing 81 which bears on the cap 63 which engages the end of the pump plunger member 27.

The casing of the appliance is provided with a fitting 82 having a filter 83, the fitting 82 receiving a pipe connection so that lubricant can be fed to its interior which is maintained full of lubricant.

The bearing 21 is provided with a sufficient number of slots or openings 84 and the cap 16 is also provided with slots 85 so that the liquid can enter the hollow cap 16.

In the case of a vehicle the drive to the worm

shaft may consist of a flexible or other shaft connected to a gear unit mounted on the speedometer drive, or to a rotating member in the gear box; or a belt and pulley drive may be employed.

5 A modification is shown in Figure 7 wherein the ring 12 is secured to the casing 10 instead of being secured to the flange 15 of the cap 16. In this construction the flange 15 is separate from the cap 16 and these two parts are separately 10 secured to the end of the casing and the arrangement is such that the casing 10, ring 12, cap 16, and the rotary distributor can be removed as a unit, leaving the flange 15 and its pipe connections undisturbed.

15 In carrying the invention into effect, regard must be paid to the relation between the diameter of the pump plunger, the area of contact between the facing at the end of the delivery arm of the rotary distributor and the ring, and the 20 cross sectional area of the conduits through which the liquid is to be forced. It is necessary that the load on the pump plunger together with the load provided by the spring 30 shall produce a pressure at the contacting surfaces of the delivery arm and conduit ring equal to or in excess of 25 that required to ensure a seal between these contacting surfaces.

25 We have found that the necessary seal is obtained when using a pump plunger one-quarter of an inch in diameter by using a spring 30 which provides a minimum load of five pounds and a passage 40 of one-sixteenth of an inch in diameter and a plug 41 having an end face which bears on the ring, this end face being five-sixteenths of 30 an inch in diameter, this arrangement being used when the angle between the balancing arms 44 and 45 is about 20° and all bearing on the same ring.

35 What we claim then is:

1. Apparatus for delivering liquids, comprising 40 a hollow body through one end of which extends a plurality of delivery openings, the inner ends of which are disposed in a circular row, a rotary distributor arranged in said body co-axially with said row of openings, a pump in said distributor, a radial arm on said distributor, said pump and said arm having a delivery passage for liquid, said arm having a facing engaging said body and the delivery passage extending through said facing and registering in turn with the ends of each of said delivery openings said facing engaging at each delivery stroke of the pump only a small marginal area of the body around the delivery opening with which the delivery passage registers, means for operating the pump, means for 45 rotating the distributor with a step by step motion to bring the end of the delivery passage successively into register with the ends of each of said delivery openings, said pump having a plunger reciprocating in the distributor parallel to the axis thereof, and means for transmitting the pressure of said plunger, on the working stroke only, to the rotary distributor to effect a pressure seal between the facing on its arm and the part of the body with which it engages.

50 2. Apparatus for delivering liquids, comprising a hollow body including a casing, one end of which is closed by a flanged cap, the flange of which has a plurality of delivery openings, and 55 a ring within the casing and secured to the inner face of the flange of the cap, said ring having an equally spaced circular row of delivery openings extending through it from side to side, which openings register with openings through the flange, a rotary distributor arranged in said

body co-axially with said row of openings, a pump in said distributor, a radial arm on said distributor, said pump and said arm having a delivery passage for liquid, said arm having a facing engaging one side of the ring and the delivery passage extending through said facing and registering in turn with the delivery openings through the ring, means for operating the pump, means for rotating the distributor with a step by step motion to bring the end of the delivery passage successively into register with the ends of each of said delivery openings in the ring, said pump having a plunger reciprocating in the distributor parallel to the axis thereof, and means for transmitting the pressure of said piston, on the working stroke only, to the rotary distributor to effect a pressure seal between the facing on its arm and the side of the ring.

3. Apparatus for delivering liquids, comprising a hollow body including a casing, one end of which is closed by a flanged cap, the flange of which has a plurality of delivery openings and a ring secured to and projecting within the casing, said ring having an equally spaced circular row of delivery openings extending through it from side to side, which openings register with openings through the flange, a rotary distributor arranged in said body co-axially with said row of openings, a pump in said distributor, a radial arm on said distributor, said pump and said arm having a delivery passage for liquid, said arm having a facing engaging one side of the ring, and the delivery passage extending through said facing and registering in turn with the delivery openings through the ring, means for operating the pump, means for rotating the distributor with a step by step motion to bring the end of the delivery passage successively into register with the ends of each of said delivery openings in the ring, said pump having a plunger reciprocating in the distributor parallel to the axis thereof, and means for transmitting the pressure of said piston, on the working stroke only, to the rotary distributor to effect a pressure seal between the facing on its arm and the side of the ring.

4. Apparatus for delivering liquids, comprising a hollow body through one end of which extends a plurality of delivery openings, the inner ends of which are disposed in a circular row, a rotary distributor arranged in said body co-axially with said row of openings, a pump cylinder in said distributor, the axis of the cylinder being at right angles to a plane containing the inner ends of said delivery openings, a two-part pump plunger in said cylinder arranged with a gap between their inner ends, said cylinder having liquid inlet and discharge ports which are spaced apart along the length of the cylinder, means for reciprocating one part of the pump plunger, means on the other part of the pump plunger for engaging an abutment in fixed relationship with the distributor during the delivery or inward movement of the first part of the pump plunger, so that the pressure thereon is transmitted to the distributor during delivery only, a radial arm on said distributor, said pump and said arm having a delivery passage for liquid, said arm having a facing engaging said body and the delivery passage extending through said facing and registering in turn with the ends of each of said delivery openings, and means for rotating the distributor with a step by step motion to bring the end of the delivery passage successively into register with the ends of each of the delivery strokes.

5. Apparatus for delivering liquids, comprising a hollow body through one end of which extends a plurality of delivery openings, the inner ends of which are disposed in a circular row, a rotary distributor arranged in said body co-axially with said row of openings, a pump cylinder in said distributor, the axis of the cylinder being at right angles to a plane containing the inner ends of said delivery openings, a two-part pump plunger in said cylinder arranged with a gap between their inner ends, means for adjusting the length of said gap, said cylinder having liquid inlet and discharge ports which are spaced apart along the length of the cylinder, means for reciprocating one part of the pump plunger, means on the other part of the pump plunger for engaging an abutment in fixed relationship with the distributor during the delivery or inward movement of the first part of the pump plunger, so that the pressure thereon is transmitted to the distributor during delivery only, a radial arm on said distributor, said pump and said arm having a delivery passage for liquid, said arm having a facing engaging said body and the delivery passage extending through said facing and registering in turn with the ends of each of said delivery openings, and means for rotating the distributor with a step by step motion to bring the end of the delivery passage successively into register with the ends of each of the delivery strokes.

6. Apparatus for delivering liquids, comprising a hollow body through one end of which extends a plurality of delivery openings, the inner ends of which are disposed in a circular row, a rotary distributor arranged in said body co-axially with said row of openings, a pump cylinder in said distributor, the axis of the cylinder being at right angles to a plane containing the inner ends of said delivery openings, a two-part pump plunger in said cylinder arranged with a gap between their inner ends, means for adjusting the length of said gap, said cylinder having liquid inlet and discharge ports which are spaced apart along the length of the cylinder, means for reciprocating one part of the pump plunger, means on the other part of the pump plunger for engaging an abutment in fixed relationship with the distributor during the delivery or inward movement of the first part of the pump plunger, so that the pressure thereon is transmitted to the distributor during delivery only, a radial arm on said distributor, said pump and said arm having a delivery passage for liquid, said arm having a facing engaging said body and the delivery passage extending through said facing and registering in turn with the ends of each of said delivery openings, and means for rotating the distributor with a step by step motion to bring the end of the delivery passage successively into register with the ends of each of the delivery strokes.

7. Apparatus for delivering liquids, comprising a hollow body through one end of which extends a plurality of delivery openings, the inner ends of which are disposed in a circular row, a rotary distributor arranged in said body co-axially with said row of openings, a pump cylinder in said distributor, the axis of the cylinder being at right angles to a plane containing the inner ends of said delivery openings, a two-part pump plunger in said cylinder arranged with a gap between their inner ends, means for adjusting the length of said gap, said cylinder having liquid inlet and discharge ports which are spaced apart along the length of the cylinder, means for reciprocating one part of the pump plunger, means on the other part of the pump plunger for engaging an abutment in fixed relationship with the distributor during the delivery or inward movement of the first part of the pump plunger, so that the pressure thereon is transmitted to the distributor during delivery only, a radial arm on said distributor, said pump and said arm having a delivery passage for liquid, said arm having a facing engaging said body and the delivery passage extending through said facing and registering in turn with the ends of each of said delivery openings, and means for rotating the distributor with a step by step motion to bring the end of the delivery passage successively into register with the ends of each of the delivery strokes.

8. Apparatus for delivering liquids, comprising a hollow body through one end of which extends a plurality of delivery openings, the inner ends of which are disposed in a circular row, a rotary distributor arranged in said body co-axially with said row of openings, a pump cylinder in said distributor, the axis of the cylinder being at right angles to a plane containing the inner ends of said delivery openings, a two-part pump plunger in said cylinder arranged with a gap between their inner ends, means for adjusting the length of said gap, said cylinder having liquid inlet and discharge ports which are spaced apart along the length of the cylinder, means for reciprocating one part of the pump plunger, means on the other part of the pump plunger for engaging an abutment in fixed relationship with the distributor during the delivery or inward movement of the first part of the pump plunger, so that the pressure thereon is transmitted to the distributor during delivery only, a radial arm on said distributor, said pump and said arm having a delivery passage for liquid, said arm having a facing engaging said body and the delivery passage extending through said facing and registering in turn with the ends of each of said delivery openings, and means for rotating the distributor with a step by step motion to bring the end of the delivery passage successively into register with the ends of each of the delivery strokes.

and a facing for engaging the body, the delivery passage extending through said facing and registering in turn with each of said delivery openings, said facing engaging at each delivery stroke of the pump only a small marginal area of the body around the delivery opening with which the delivery passage registers.

8. Apparatus for delivering liquids, comprising a hollow body through one end of which extends a plurality of delivery openings, the inner ends of which are disposed in a circular row, a rotary distributor arranged in said body co-axially with said row of openings, a pump cylinder in said distributor, the axis of the cylinder being at right angles to a plane containing the inner ends of said delivery openings, a two-part pump plunger in said cylinder arranged with a gap between their inner ends, said cylinder having liquid inlet and discharge ports which are spaced apart along the length of the cylinder, a spring-loaded cap slidably mounted in one end of the distributor, said cap bearing on the end of one part of the pump plunger, means acting on this cap for driving said pump plunger part inwardly, a second cap secured to the opposite end of the distributor forming an abutment receiving pressure from the second part of the pump plunger during the delivery stroke, a radial arm on said distributor, said pump and said arm having a delivery passage for liquid, said arm having a facing engaging said body and the delivery passage extending through said facing and registering in turn with the ends of each of said delivery openings, and means for rotating the distributor with a step by step motion to bring the end of the delivery passage successively into register with the ends of each of said delivery openings, said means operating between the delivery strokes.

9. Apparatus for delivering liquids, comprising a hollow body through one end of which extends a plurality of delivery openings, the inner ends of which are disposed in a circular row, a rotary distributor arranged in said body co-axially with said row of openings, a pump cylinder in said distributor, the axis of the cylinder being at right angles to a plane containing the inner ends of said delivery openings, a two-part pump plunger in said cylinder arranged with a gap between their inner ends, said cylinder having liquid inlet and discharge ports which are spaced apart along the length of the cylinder, a spring-loaded cap slidably mounted in one end of the distributor, said cap bearing on the end of one part of the pump plunger, means acting on this cap for driving said pump plunger part inwardly, a second cap secured to the opposite end of the distributor forming an abutment receiving pressure from the second part of the pump plunger during the delivery stroke, said second part of the pump plunger having a shoulder within the cap for engaging the inner surface of the end of said cap, a flange on said second pump plunger part, a spring within the cap acting on said flange, said second pump plunger part extending through the end of said cap, a sleeve fixed on the end of said second plunger part exterior to the cap, an adjusting pin extending transversely through the adjacent part of said hollow body, said pin engaging said sleeve for adjusting the length of the gap between the inner ends of the two pump plunger parts, a radial arm on said distributor, said pump and said arm having a delivery passage for liquid, said arm having a facing engaging said body, and the delivery passage extending through said facing and registering in turn with the ends of each

of said delivery openings, and means for rotating the distributor with a step by step motion to bring the end of the delivery passage successively into register with the ends of each of said delivery openings, said means operating between the delivery strokes.

10. Apparatus for delivering liquids, comprising a hollow body through one end of which extends a plurality of delivery openings, the inner ends of which are disposed in a circular row, a rotary distributor arranged in said body co-axially with said row of openings, a pump in said distributor, a plurality of radial arms on said distributor, said pump and one of said arms having a delivery passage for liquid, said arms engaging said body, and the arm with the delivery passage having a facing through which the passage extends, the end of said passage registering in turn with the ends of each of said delivery openings, means for operating the pump, means for rotating the distributor with a step by step motion to bring the end of the delivery passage successively into register with the ends of each of said delivery openings, said pump having a plunger reciprocating in the distributor parallel to the axis thereof, and means for transmitting the pressure of said plunger, on the working stroke, to the rotary distributor to effect a pressure seal between the facing on its arm and the part of the body with which it engages.

11. Apparatus for delivering liquids, comprising a hollow body through one end of which extends a plurality of delivery openings, the inner ends of which are disposed in a circular row, a rotary distributor arranged in said body co-axially with said row of openings, a pump in said distributor, a radial arm on said distributor, said pump and said arm having a delivery passage for liquid, said arm having a facing engaging said body and the delivery passage extending through said facing and registering in turn with the ends of each of said delivery openings, means for operating the pump, a ratchet wheel fixed on the distributor concentrically with its axis, a ring mounted on said distributor for oscillatory movement, means for oscillating said ring, a pawl carried by said ring and engaging the ratchet wheel, a stationary ratchet wheel mounted adjacent the distributor and having its teeth directed oppositely from the teeth of the ratchet wheel on the distributor, a pawl on the distributor traversing the teeth of said stationary ratchet wheel, said pump having a plunger reciprocating in the distributor parallel to the axis thereof, and means for transmitting the pressure of said plunger, on the working stroke, to the rotary distributor to effect a pressure seal between the facing on its arm and the part of the body with which it engages.

12. Apparatus for delivering liquids, comprising a hollow body through one end of which extends a plurality of delivery openings, the inner ends of which are disposed in a circular row, a rotary distributor arranged in said body co-axially with said row of openings, a pump in said distributor, a radial arm on said distributor, said pump and said arm having a delivery passage for liquid, said arm having a facing engaging said body and the delivery passage extending through said facing and registering in turn with the ends of each of said delivery openings, a bearing hub fixed within said hollow body, a face cam mounted on said hub for rotation, means for rotating said cam, said cam operating the pump, means for rotating the distributor with a step by

step motion to bring the end of the delivery passage successively into register with the ends of each of said delivery openings, said pump having a plunger reciprocating in the distributor parallel to the axis thereof, and means for transmitting the pressure of said plunger, on the working stroke, to the rotary distributor to effect a pressure seal between the facing on its arm and the part of the body with which it engages.

13. Apparatus for delivering liquids, comprising a hollow body through one end of which extends a plurality of delivery openings, the inner ends of which are disposed in a circular row, a rotary distributor arranged in said body co-axially with said row of openings, a pump in said distributor, a radial arm on said distributor, said pump and said arm having a delivery passage for liquid, said arm having a facing engaging said body and the delivery passage extending through said facing and registering in turn with the ends of each of said delivery openings, means for operating the pump, a ratchet wheel fixed on the distributor concentrically with its axis, a ring mounted on said distributor for oscillatory movement, a bearing hub fixed within said hollow body, a face cam mounted on said hub for rotation, means for rotating said cam, said cam operating the pump, an eccentric pin projecting axially from the end of said cam, a slotted arm on said ring, means on said eccentric pin engaging in the slot of the arm for oscillating the ring as the cam rotates, a pawl carried by said ring and engaging the ratchet wheel, a stationary ratchet wheel mounted adjacent the distributor and having its teeth directed oppositely from the teeth of the ratchet wheel on the distributor, a pawl on the distributor traversing the teeth of said stationary ratchet wheel, said pump having a plunger reciprocating in the distributor parallel to the axis thereof, and means for transmitting the pressure of said plunger, on the working stroke, to the rotary distributor to effect a pressure seal between the facing on its arm and the part of the body with which it engages.

14. Apparatus for delivering liquids, comprising a hollow body through one end of which extends a plurality of delivery openings, the inner ends of which are disposed in a circular row, a rotary distributor arranged in said body co-axially with said row of openings, a pump in said distributor, a radial arm on said distributor, said pump and said arm having a delivery passage for liquid, said arm having a facing engaging said body and the delivery passage extending through said facing and registering in turn with the ends of each of said delivery openings, a bearing hub fixed within said hollow body, a face cam mounted on said hub for rotation, means for rotating said cam, an idler arm pivoted within the hollow body having a portion engaged by said cam and a portion driving the pump, means for rotating the distributor with a step by step motion to bring the end of the delivery passage successively into register with the ends of each of said delivery openings, said pump having a plunger reciprocating in the distributor parallel to the axis thereof, and means for transmitting the pressure of said plunger, on the working stroke, to the rotary distributor to effect a pressure seal between the facing on its arm and the part of the body with which it engages.

15. Apparatus for delivering liquids, comprising a hollow body through one end of which extends a plurality of delivery openings, the inner ends of which are disposed in a circular row, a rotary distributor arranged in said body co-axially with said row of openings, a pump in said distributor, a radial arm on said distributor, said pump and said arm having a delivery passage for liquid, said arm having a facing engaging said body and the delivery passage extending through said facing and registering in turn with the ends of each of said delivery openings, a bearing hub fixed within said hollow body, a face cam mounted on said hub for rotation, a worm wheel fixed to said cam, a worm shaft mounted on bearings in the body, a worm on said shaft engaging said worm wheel, means for rotating the distributor with a step by step motion to bring the end of the delivery passage successively into register with the ends of each of said delivery openings, said pump having a plunger reciprocating in the distributor parallel to the axis thereof, and means for transmitting the pressure of said plunger, on the working stroke, to the rotary distributor to effect a pressure seal between the facing on its arm and the part of the body with which it engages.

16. Apparatus for delivering liquids, comprising a hollow body, through one end of which extends a plurality of delivery openings, the inner ends of which are disposed in a circular row, a rotary distributor arranged in said body co-axially with said row of openings, a reciprocating pump in said distributor, an outwardly projecting arm on said distributor, said pump and said arm having a delivery passage for liquid, said arm engaging said body, and the delivery passage extending through said arm and registering in turn with the ends of said delivery openings said arm engaging the body, at each delivery stroke of the pump, over a small marginal area only around the delivery opening with which the delivery passage registers, means for operating the pump, means for rotating the distributor with a step by step motion to bring the end of the delivery passage in the arm successively into register with the ends of said delivery openings, said pump having a plunger reciprocating in the distributor parallel to the axis thereof, and means for transmitting the pressure of said plunger on the working stroke only and when the distributor is stationary only, to the distributor to effect a pressure seal between the end of the said arm and the part of the body with which it engages.

HARRY PARKER.
